KNOCK-DOWN FURNITURE

Paul E. Freeman, Tallahassee, Fla., assignor to Lok Trim Corporation, Tallahassee, Fla., a corporation of Florida
Filed Dec. 6, 1962, Ser. No. 242,762
5 Claims. (Cl. 312—255)

This application is a continuation-in-part of my earlier application Serial No. 178,289 filed March 8, 1962. This invention relates to knock-down furniture and is directed primarily to furniture which is capable of easy and ready assembly and disassembly, such as bookcases, modular store furniture of various types, receptacles and the like.

An important object of the invention is to provide a knock-down furniture structure wherein the various components of the respective structures are capable of ready assembly and disassembly which generally precludes the use of any specific fastening elements such as nails, screws, or the like, whereby consequently the various elements of the finished furniture desired are capable of shipment in knock-down condition, after which the same can be readily assembled by persons unskilled in the art and without any specific knowledge of furniture assembling.

One of the more important objects of the present invention is to provide a knock-down furniture structure capable of being assembled under a predetermined method of plan, which when followed, produces a set-up unitary structure.

Another object of the invention is to provide in substantially each completed furniture unit, substantially identical extruded metal angle or channel members, each of the channel members having longitudinally extended right angle sides, said sides being provided at their inner free ends with inturned flanges, which in effect produce a box-like structure. These channel members are capable of engagement along the respective joined edges of the furniture components to effectively provide a unitary structure.

A further and important object of the invention is to provide the respective channeled corner members with an internal filler member, which filler member completes a closed leg structure or corner member which lends to neat appearance and strength in the finished product.

A further object of the invention is to provide shelf supporting members or brackets which are capable of movement to various positions to support a plurality of shelves at various points, as in a knock-down bookcase, or the like.

A further object of the invention is to provide a foot portion for the various leg portions of such a cabinet upon which the cabinet is capable of standing. And it is intended that the foot portions likewise be used in certain constructions as a cap portion at the upper ends of the various legs.

Various other objects and advantages of the invention will be appreciated and will become apparent when considered in connection with the accompanying description and drawings, in which like numerals indicate similar parts throughout the various views:

FIG. 1 is a perspective view of a bookcase or the like embodying the invention;

FIG. 2 is an exploded view of the bookcase of FIG. 1;

FIG. 3 is a section taken on the line 3—3 of FIG. 1;

FIG. 4 is a perspective view of a box-like structure embodying the invention;

FIG. 5 is an exploded view of the structure disclosed in FIG. 4;

FIG. 6 is a section on the line 6—6 of FIG. 4;

FIG. 7 is a section on the line 7—7 of FIG. 4;

FIG. 8 is an enlarged view of one of the angle irons, support and its associated filler and foot portion of the structure seen in FIG. 4;

FIG. 9 is an exploded view of FIG. 8;

2

FIG. 10 is an exploded view of the lower portion of one of the leg elements disclosing the foot member;

FIG. 11 is an exploded view showing one of the foot members and the manner in which it is attached to the frame member, further showing a furniture slide;

FIG. 12 is a perspective view of a modified cap structure;

FIG. 13 is a perspective view of a portion of the upper end of the box-like structure of FIG. 4, showing the modified cap structure of FIG. 12; and

FIG. 14 is an enlarged view of one of the corners of the structure of FIG. 13, showing the manner in which the cap is mounted.

Referring more specifically to the drawings, in which

like numerals are used to designate similar parts throughout the various views, a knock-down bookcase structure is generally indicated at 6 in FIG. 1. The structure disclosed therein is provided with a bottom panel 7, a top panel 8, side panels 9 and 10 and an intermediate shelf 11. The

bookcase structure disclosed is provided with a rear wall 12. It will be noted that the bottom panel 7, as seen in FIG. 2, is provided along its opposite side edges with mitered portions 13, said mitered portions are not, in the

sense of the term, truly mitered, but each is provided with

an offset 14 for a purpose later to be described. Each of the sides 9 and 10 of the bookcase is provided along its upper and lower edges with mitered portions 15, 16, 17 and 18, each of the mitered portions 15, 16, 17 and 18

being provided with cut-out offset portions 19, the purpose

30 thereof to provide a means whereby when the respective mitered sections of the respective panels are moved into engagement or abutting relation, the offset portions 14 of the side edges of bottom panel 7 will be received in the recess 19. Likewise, the top or upper panel 8 is provided

35 along its opposite edges with mitered joints 13 and provided with offsets 14 substantially identical to the offsets

14 described with respect to panel 7, and in a like manner engage within the cut-out portions 19 of the upper edges

30 of the side panels 9 and 10 when the panels are moved into

40 abutting relation. It will be noted that the respective edges of the panel members just described are slightly cut away as indicated at 29, whereby the same are capable of

45 accommodating thickness of the side of the respective connecting channel members so that the latter, later to be de-

scribed, will lie flush with the respective panel surfaces of

50 the cabinet. The back wall 12 is a single panel and is moved into position along the vertical slots 21 rabbeted

55 along the rear portions of the respective side members 9 and 10, the bottom edge of the panel 12 being received

50 within a slot 22 rabbeted within the upper surface and at the rear portion of the bottom panel 7. The intermediate shelf 11 is capable of longitudinal sliding fit as along its

55 respective side edges within the horizontally disposed kerfs or rabbets 24 provided along the inner sides of the panels

9 and 10 for receiving the same.

It will be apparent that the bottom panel 7 and the side panels 9 and 10 are provided inwardly of their marginal edges and along their outer surfaces with rabbets

25 for accommodating the inturned edges of the respective

60 channel members which are utilized in assembling the structure, the channel members later to be described.

As shown, the various elements of the structure are

65 moved into assembled relation and held in this relation through the means of angle-shaped or channel elements,

65 which are the only means relied upon for supporting the knock-down structures in their assembled relation. Thus,

70 referring to FIGS. 1 and 2 in particular, the channel members which are substantially identical in form and

capable of extrusion from a single die, the length of

70 which can readily be varied, are disclosed and comprise two upper channel members 26 and 27, these channel members being provided with mitered edges 28 for a

purpose to be described. The structure also includes two alike lower horizontal channel members 29 which comprise right angularly related longitudinally extending side members, said side members terminating in right angularly inturned flange portions 30. Each of the vertical four corner portions of the described structure are provided with vertically disposed channel members 31, all of which are substantially identical to the channel members 26, 27 and 29, the only difference being in the respective lengths thereof and their end configurations. Thus, the vertical channel members 31 are likewise provided with angularly inturned flange portions 30, the upper edges of the member 31 being mitered as at 32, said mitered portion engaging the mitered portions 38 of the channel members 26 and 27 when moved to abutting relation. The lower ends of these respective vertical corner sections are provided at their lower ends with shelf supporting members 34 which will later be described in more detail. The intermediate shelf 11 is provided along its front edges with notches, which notches are for the purpose of receiving the angularly inturned flanges 30 of the corner members 31 when the latter are slid vertically into position.

In the assembly of the structure disclosed in FIGS. 1 and 2, it is first only necessary to move the sides 9 and 10 inwardly until the mitered portions of each side member adjacent its lower edges are moved into mitered or abutting engagement with the mitered portions 13 of the bottom panel 7. Next, the back panel 12 is fitted downwardly with its side edges in the slots 21, the bottom edge resting within the groove 22. This being accomplished, the top panel 8 is then moved into position with its mitered side edges 13 into engagement with the upper mitered edges 16 and 18 of the respective sides 9 and 10. In this partially assembled relation the channel members 26 and 27 with their inturned angular flange portions (not shown) are slid longitudinally within the respective recesses 25 whereupon the two side panels and the top panel are now in relatively fixed relation. Next, the channel members 29 with their respective inturned feet portion 30 are slid longitudinally to confine the bottom panel 7 and the two side panel members 9 and 10. This having been done, the respective corner channel members 31 are slid vertically upwardly, the inturned feet portion 30 engaging the rabbets 25 provided therefor along the outer surfaces of the panels 9 and 10, whereupon the mitered portions 32 lie in abutting engagement with the mitered portions 28 of the upper channel members 26 and 27. In such a condition the article of knock down furniture is in its substantially erected condition. It, of course, will be understood that the shelf 11 will be slid horizontally within the slots 24 as heretofore described, and consequently, the channel members 31 when moved into position, their inturned portions 30 will engage within the recess 33 to hold the shelf 11 in proper relation.

The bottom shelf panel supporting structure generally shown in FIG. 2, and more specifically shown in greater detail in FIGS. 8 and 9, comprises a bracket type supporting member 34, which is provided adjacent one of its ends with an opening 35, which opening will accommodate a screw or the like which is capable of passing upwardly through the opening into engagement with the lower panel, which panel is supported at its respective corners upon the bracket 34. Consequently, when desired, the shelf can merely be positioned upon the supporting brackets 34; or, as indicated, it can be fastened thereto as by screws passing through the openings 35. The vertical channel members 31 are readily seen in FIGS. 8 and 9 and comprise right angularly related side members which terminate in inturned flange members 30. These channel members are provided with a filler 36, said filler comprising a substantially U-shaped central portion 37 providing a spaced vertical opening 38, the opening at its respective sides terminating in right angularly disposed side portions 39 and 40. These respec-

tive side portions terminate in angularly recessed portions 41, which portions are shaped to accommodate the inturned flange portions 30 of the channel members 31. The filler 36 has projecting rearwardly from its U-shaped part 37 a web 42, which web engages within the angle provided by the two side faces of the channel member 31. The substantially U-shaped portion 37 of the filler 36 is provided on its inner surface with a threaded portion 43 for a purpose to be described. The bracket 34 is provided at its inner end with a right angularly disposed portion 44, the right angular portion terminating adjacent its inner edges in notches 45 along its respective sides. These notches are capable of a sliding fit with the inturned flanges 30 moving therein. It will be noted that the filler 39 has been cut off a distance equal to the thickness of the bracket 34, whereby the bracket 34 can be guided within the flanges 30 and the notches 45 to a position of support upon the upper surface of the filler 36. In order to lock the bracket 34 to the filler 36 and within the channel member 31, the bracket is provided with an opening 46 which is adapted to receive a screw 47. In assembling the bracket 34 to the channel 31 and the filler 39, the bracket is moved into position within the channel 31, whereupon the screw 47 is passed through the opening 46 into engagement with the threaded portion 43 of the filler 36. Thus, when the screw is driven home, the bracket 34 is anchored in locked position whereupon to support the bottom panel 7.

As shown in FIGS. 10 and 11, a furniture foot and furniture slide are disclosed. As seen in these two figures in particular, the substantially U-shaped portion 37 of the filler 36 is threaded as indicated at 43. The foot 48 is substantially square in cross section so that it will, when screwed home, register with the respective sides of the channel member 31 and filler 36. The foot 48 is provided with a threaded extension 49, which extension is of tubular shape and is inwardly threaded, as at 50. The inner threads 50 are adapted to receive the threaded shank 51 of a furniture slide 52. In the assembly of the foot and slide, the foot member 48 is screwed into the threaded portion 43 of the filler 36 until it is moved to lie flush with the bottom surface of the channel 31, and the respective sides of the foot register with the sides of the channel 31. This having been done, the furniture slide 52 is screwed into the threaded portion 50 of the extension 49. It is not necessary that the furniture slide 52 be screwed all of the way in, and it will consequently be seen that the furniture slide 52 can be screwed to a position to level the article of furniture.

Referring now specifically to the structure of the cabinet shown in FIG. 4, it should be emphasized that the structure shown here is primarily a modification of the structure disclosed in FIG. 1 and that the object of showing these figures is to depict the manner in which other pieces of knock-down furniture are capable of assembly and disassembly. The structure shown in FIG. 4, however, differs only in minor respects, that is, primarily in shape from the disclosure of FIG. 1, in that the open receptacle disclosed does not include a top panel or a shelf panel.

The construction shown herein shows a receptacle, including a bottom and four side panels, with the elimination of a top panel. However, the structure disclosed is united in substantially the identical manner as the furniture disclosed in FIG. 1. Consequently, the numerals used in FIGS. 4, 5, 6 and 7 are substantially identical to the numerals used with respect to the disclosure of FIG. 1, with the exception that the numerals have been primed where convenient to indicate similar parts.

Thus, the structure shown in FIGS. 4 and 5 in particular comprises vertical channel members 31' which are substantially identical to the channel members 31 and are provided with inturned flange members 30'. The container disclosed comprises a bottom panel 53, two side panels 9' and 10' and front and rear panels 54 and

55. Referring to the bottom panel 53, it will be seen that the respective inner edges thereof are mitered as at 13'. The side panels 9' and 10' are, as described with respect to the panels 9 and 10 in FIG. 2, provided with cut away portions 20' and horizontal and vertical rabbets 25'. The panel 10' is provided with miters 17' and offset portion 19'. While in FIG. 1 the front edges of the panels 9 and 10 are shown as being square, in the construction here described, the side panels 9' and 10' are provided along their respective edges with mitered portions 56. Likewise, with respect to the front and rear panels 54, they are each cut away as at 20' and are provided with mitered portions 56 along their inside lower edge surfaces and mitered portions 57 along their vertical offset inside edge portions. The rear panel 55 is likewise mitered along its lower inside edge as at 58 and along its vertical inside edges as at 59.

In the assembly of the structure disclosed in FIGS. 4 and 5, it is only necessary to move the respective side and front and rear panels inwardly toward the base or lower panel 53 to a position where the mitered lower portions of the referred to respective panels are in abutting relation with respect to each other. In such position it is only necessary to slide the channel members 29' longitudinally, whereby the flanged portions 39' thereof engage with the rabbeted portions 25' formed on the lower side of the panel 53 and likewise along the lower edge portions of the side panel 9'. Next, the channel member 29' on the opposite lower side of the article is moved into position. In this condition the bottom panel 53 and the two side panels 9' and 10' are held in substantial position. Thereafter, the front panel 54 and the rear panel 55 is moved into position whereby the mitered portions 56 and 58 of the respective panels engage or abut the mitered portions 13' of the bottom panel. In this condition the lower channel shaped members 60 and 61 with their inturned angle portions 61' engage within the rabbets 25' formed adjacent the edges and on the outer face of the lower panel 53 and likewise adjacent the edges on the outer face of the lower edges of the front panel 54. It will be noted that the channel members 26' and 27' can readily be mounted upon the upper portions of the side panels 9' and 10' in which position, of course, their mitered corners 28' will overhang respective edge portions of the panels. The article being set up in this position, it is now only necessary to vertically move the corner channel members 31' into position and as will be seen, when these corner channel members are moved into vertical position, the upper mitered edges 32' thereof engage in abutting relation with the mitered portions 28' of the upper channel members 26' and 27'. In this condition the receptacle is mounted in assembled relation.

It will be understood that the angle members 62 and 63 embracing the upper edges of the front and rear panels 54 and 55 respectively are primarily for purposes of ornamentation, that is, to give the upper edges of these two panels a finished look corresponding to the respective corners of the rest of the structure. The channel members 62 and 63 are likewise provided with angularly inturned portions 64, as best seen in FIG. 6. The inturned portions 64 are adapted to be received in recesses or grooves formed within the respective panels 54 and 55, it further being noted that the top and rear faces of these two panels have been cut away a thickness substantially equal to the thickness of the surfaces of the channel members 62 and 63, whereby the channel members will lie flush with the surfaces of the panels 54 and 55. The supporting brackets 34' heretofore described with respect to FIG. 1 are identical to the supporting brackets 34 of that figure, and the brackets are supported in the same manner as that described with respect to the structure of FIG. 1 and the brackets 34' can be fastened as by screws passing through the holes 35' to the bottom panel 53, if and when desired. It will be seen that the

corner members 31', below the supporting brackets 34' are provided with the filler 36' identical to the filler 36 of FIG. 9.

The modifications disclosed in FIGS. 12, 13 and 14 are directed primarily to a novel finishing cap structure which could readily be substituted in the upper portion of the structure disclosed in FIG. 4. In this modification of cap structure, the receptacle comprises a bottom panel 80, two side panels 81 and 82 and front and rear panels 83 and 84. The upper portions of the respective panels 81, 82, 83 and 84 are provided with channel members 85 which are substantially identical and are provided with inwardly directed flanges 86 which are capable of engagement within grooves preformed within the upper edges of the respective panels, it, of course, being understood that the upper edges of the respective panels have been cut away the thickness of the various walls of the brackets 85, whereby, when the brackets are moved into position, they will lie flush with the outer panel surfaces, primarily for decorative reasons.

The cap member 93, as seen in FIG. 12, is provided with substantially triangular shaped ears 87 extending horizontally from the upper portion of the cap 86. These triangular shaped ears 87 are capable of being inserted within recesses 88, which recesses have been provided in the upper surfaces of the side members 81 and 83. Each of the respective vertically disposed meeting corners of the respective panels 81, 82, 83 and 84 is provided with mitered portions 14" and 19", substantially identical to the structure disclosed in FIG. 7. The vertical corners of the box-like structure disclosed in FIG. 18 are, of course, enclosed within the like channel members 83 which are likewise provided with inturned flanges 89. The cap member 93 is provided with vertically disposed surfaces 90 which terminate in reduced angular portions 91. These portions 91 are capable of being moved into recesses 92, said recesses having been cut away in the respective edges of the side members 81 and 83 for accommodating the same. It will be understood that each of the corners is finished in substantially an identical manner. Thus, in the assembly of the structure disclosed in FIGS. 18 and 19 the respective walls are moved into position with respect to the bottom panel 80, whereupon the four cap members 93 are moved into position to cover the four corners. Thereafter, the respective channel members 85 and 88 are moved into position wherein the inner ends of the channel members 85 and 88 pass over the ears 87 and the extensions 91 to thereby lock the cap in place and consequently provide an ornamental cap for the respective corners.

50 In consequence of the above disclosure, it will readily be recognized that I have provided a relatively simple and unique means of providing a plurality of knock-down furniture elements which can be readily assembled and disassembled by persons unskilled in the art, generally requiring no tools and capable of fast assembly and disassembly; further, by the construction disclosed the various units are highly desirable in appearance in view of the fact that all of the exposed edges are covered by channel members, preferably extruded from aluminum or the like, producing a desirable appearance. Further, the structure is extremely strong in that the channel members have incorporated therein various interior filler elements which provide desirable strength characteristics.

65 It will be readily recognized from a consideration of the above disclosures that I have provided an extremely unique and novel means of producing a plurality of different type knockdown furniture units. Thus, it is contemplated that, from the structures disclosed, that many 70 different type knock-down structures are capable of quick and easy assembly and disassembly and that various modular constructions are possible and capable within the disclosed construction. Further, a novel foot and furniture slide arrangement is disclosed, which foot is capable of not only use as a foot but as a cap member. Again, vari-

ous type cap members are capable of use as disclosed with respect to the cap member of FIG. 12, which shows a novel means of inserting an ornamental cap member at the respective corners of a knock-down unit.

From an overall consideration it is contemplated that the invention describes a novel method of assembling various knock-down furniture structures, the various structures including substantially identical extruded aluminum angle members, the various panels of the respective members having mitered portions and further being rabbeted along various edges whereby the respectively panels can be moved into abutting relation and thereafter held in erected position as by the movement of the respective channel members to their various positions.

It will be understood that the constructions disclosed are for exemplary purposes only and that various changes and modifications are capable within the scope of the following claims.

I claim:

1. A knock-down furniture construction comprising in combination a bottom panel and side panels, said bottom panel having its side edges cut on a miter, the said side panels having their lower and vertical edges cut on a miter, the mitered portions of the bottom and side panels abutting each other when the furniture is in assembled relation, and a plurality of substantially identical horizontally and vertically disposed angularly shaped channel members having angularly inturned flanges, said bottom and side panels having rabbets formed on their outer faces adjacent the mitered edges, said channel members enclosing the abutted miter portions of the respective panel members with the inturned flanges of the channel members engaged within the said rabbets to support the furniture in erect condition, the said channel members including a substantially U-shaped filler provided with angularly disposed sides to complete a box-like structure, said channel members and U-shaped filler extending below the bottom panel and providing a furniture leg support.

2. The structure according to claim 1, and a panel supporting bracket having its rear end disposed within the channel member and resting on top of the said filler, and an attaching member for the bracket extending through the same into locking engagement with the filler.

3. The structure according to claim 1, said vertical channel and filler members having a foot, said foot having a stud extending therefrom engageable with the filler to lock the foot to said channel and filler.

4. The structure according to claim 3, and a furniture slide caster having a threaded stud threadedly engaged with the foot stud.

5. A knock-down furniture construction comprising in combination, a bottom panel, side panels, and front and rear panels, a plurality of right angle channels having inwardly directed angularly disposed locking flanges, each of the edges of the side, front and rear panels having mitered edges fitting in abutting relation, said panels having grooves for receiving the locking flanges of the channels, said channels disposed along the vertical abutting mitered edges and similar channels disposed along the top edges of the recited panels, the said channels at the respective upper corners of the furniture leaving an exposed portion, and a corner cap member for covering said exposed corner portions, said cap having a pair of horizontally disposed ear members and vertically disposed reduced angle members, said ears fitting beneath the ends of the horizontal channel members, and the vertical reduced angle members fitting beneath the end of the vertical channel, said corner cap having a raised upper surface and raised side surfaces, said surfaces disposed flush with the outermost surfaces of the channel members.
